METHOD FOR USE IN LASTING SHOES

Philip E. Burby, Beverly, Mass., assignor to United
Shoe Machinery Corporation, Flemington, N. J.,
a corporation of New Jersey

Application April 30, 1947, Serial No. 744,955

8 Claims. (Cl. 12—145)

1

This invention relates to methods for use in lasting shoes and has more particular reference to the holding or securing of end portions of uppers in lasted position. The invention is herein illustrated as applied to the lasting of the toe ends of shoes of the Goodyear welt type, but it will be understood that in some aspects it is not thus limited in its applicability.

In lasting the toes of shoes of the above-mentioned type it is the common practice to apply a binder wire about the toe end of each shoe in engagement with the marginal portion of the upper over the insole for holding the upper in lasted position and to fasten the ends of the binder to the shoe by tacks driven at the opposite sides of the shoe bottom. After the welt-attaching operation the binder and the tacks are removed from the shoe. Objects of this invention are to secure the upper in lasted position by the use of a binder of such character that it need not be removed from the shoe, to eliminate the need for tacks or other fastenings for holding the binder in place, and further to utilize a binder which will apply effective holding force to the upper and will not interfere with the needle of the welt-sewing machine. With these and other objects in view, the invention, in one aspect, provides a method in accordance with which a binder of elastic material is applied in a stretched condition about an end of a shoe in engagement with an upstanding margin of the upper over the shoe bottom and is fastened to the shoe in that condition to hold the upper. Such a binder may consist, for example, of a strand of rubber, either natural or synthetic, or of any plastic material having the desired characteristics. For use on a shoe of the Goodyear welt type having an insole with an upstanding lip thereon, as herein shown, the strand of binder material will be of such thickness as to lie, when stretched, against the upper in the angle between the feather and the lip of the insole without interfering with the attachment of a welt to the shoe. Further in accordance with the method, in another aspect, such an elastic binder, applied as above described or otherwise, is fastened to the shoe by forcing it through portions of the shoe materials at the sides of the shoe bottom. As herein illustrated, portions of the binder near its ends are forced, in a stretched and therefore attenuated condition, through the margin of the upper and the lip of the insole in the form of loops, the contraction of the looped material when released resulting in such increase in its thickness as to hold the binder effectively in place.

2

The novel method will now be more particularly described with reference to the accompanying drawings and thereafter pointed out in the claims.

In the drawings,

5 Fig. 1 is a view in elevation and partly in section, showing a binder-fastening tool which may be used in the practice of the method in its relation to a shoe mounted in a toe-lasting machine preparatory to the fastening of an end portion of binder material to the shoe at one side of the shoe bottom;

Fig. 2 is a section on the line II—II of Fig. 1;
Fig. 3 is a section on the line III—III of Fig. 1;

10 Fig. 4 is a section on the line IV—IV of Fig. 1 on an enlarged scale;

Fig. 5 is a perspective view of a needle included in the tool;

15 Fig. 6 is a view partly in plan and partly in section, showing a portion of the lasting machine 20 and showing the needle of the tool in the act of forcing the binder material through the margin of the upper and the lip of the insole;

Fig. 7 is a vertical sectional view on an enlarged scale, showing parts of the tool in the 25 same positions as in Fig. 6;

Fig. 8 is a view similar to Fig. 7, but showing the parts as they appear after the needle has started to withdraw from the shoe;

30 Fig. 9 is a view similar to Fig. 6, but illustrating the operation of the binder-fastening tool at the other side of the shoe-bottom after the binder has been applied to the upstanding margin of the upper around the toe; and

Fig. 10 is a perspective view of the forepart of 35 the shoe after the binder has been applied and fastened thereto.

The method provided by this invention may be conveniently practiced in the lasting of the toe ends of welt shoes with a machine such as shown in United States Letter Patent No. 2,160,846, granted on June 6, 1939, on an application of F. C. Eastman's and A. F. Pym's, but it will be understood that it is not dependent upon the use of a machine of that particular construction to prepare the shoe to receive the toe binder. Such a machine is provided with a pair of toe-embracing wipers 2 which wipe the toe end of the upper heightwise of the last and wipe its marginal portion inwardly over the feather of the insole and against a lip α on the insole while the shoe is clamped between an insole-engaging member 4 and a toe rest 6. As disclosed in the above-mentioned Letters Patent, the machine comes to a stop after the wipers have thus wiped the upper inwardly to permit the operator to

fasten an end of a binder wire to a tack at one side of the shoe bottom and to apply the wire preliminarily against the upper around the toe adjacent to the wiping faces of the wipers. After the machine is again started the wipers are lifted slightly and are partially retracted lengthwise of the shoe and opened to enable the operator to pull the wire inwardly against the upstanding margin of the upper lying against the lip of the insole, after which they are again fully advanced and closed to press the wire against the upper and are moved downwardly to increase their pressure on the upper. The machine then comes again to a stop to permit the operator to fasten the wire to a tack at the other side of the shoe bottom and to sever the binder from the rest of the wire. In practicing the method of the present invention the operator uses, instead of wire, a strand *b* of elastic binder material, which may be rubber or other suitable material, as hereinbefore explained, and may be obtained from a reel. This strand of material will be of such thickness that when stretched it will hold the upper as required in the angle between the feather and the lip of the insole without interfering with the attachment of the welt to the shoe in the usual manner. The operator fastens an end portion of the elastic binder material to the shoe at one side of the shoe bottom in a manner hereinafter explained after the machine has come to a stop the first time, and after it has again been started he pulls the strand of material inwardly under the wipers and against the upstanding margin of the upper while stretching it lengthwise of the edge of the shoe bottom. When the machine has again come to a stop with the wipers in pressing and holding relation to the upper and the binder material, the operator fastens the latter at the other side of the shoe bottom and severs the portion applied to the shoe from the rest of the material.

Further in accordance with the present invention the binder material is fastened to the shoe at the opposite sides of the shoe bottom by forcing portions of it in a stretched condition through the margin of the upper and the lip of the insole in the form of loops and then releasing the loops to permit them to contract at the inner side of the lip, the increased thickness of the looped material by reason of such contraction anchoring the binder effectively in place in its stretched condition. For thus fastening the binder material when the toe is lasted by the use, for example, of a lasting machine such as shown in the previously mentioned Letters Patent, there may be conveniently utilized the hand tool shown in Fig. 1. This tool includes a casing 10 having integral therewith a handle 12 to assist the operator in positioning it first in a relation to the shoe such as illustrated in Fig. 1. Mounted to slide along guideways in the casing is a bar 14 an end portion of which is arranged to extend downwardly when the tool is positioned as in Fig. 1 and is provided at its lower end with projections 16 spaced from each other and arranged to engage the bottom face of the insole to determine the position of the tool heightwise of the shoe and in the operation of the tool also to engage the inner face of the lip *a* of the insole. Formed on the bar 14 are rack teeth 18 engaged by a pinion 20 rotatably mounted on a pin 22 in the casing 10, and also engaged by this pinion on its opposite side from the bar 14 are rack teeth 24 formed on an upraised central portion 26 of a slide 28 movable along guideways in the casing in parallel relation to the bar 14. Ex-

tending into the slide 28 from its left-hand end (Fig. 2) as far as its upraised portion is a recess 30. Supported on the top of the slide 28 is a shorter slide 32 having a recess 34 therein to clear the upraised portion of the slide 28. Extending downwardly from the left-hand end of the slide 32 into slots 36 in the sides of the slide 28 are two lugs 38 to limit relative movement of the two slides. Mounted in a socket in the slide 32 and engaged by the right-hand end of the upraised portion of the slide 28 is a compression spring 40. The purpose of the slide 32 is to clamp a portion of the binder material *b* against two spaced upwardly extending fingers 42 fast on the upper end of a rod 44 movably mounted in the casing 10. Such clamping action takes place upon movement of the slide 32 toward the right through the spring 40 by movement of the slide 28 in that direction. For imparting that movement to the slide 28 a handle 46 is pivotally mounted on a pin 48 in the casing 10 and has integral therewith a forked arm 50 extending upwardly into the recess 30 in the slide 28 and provided with a pin 52 rotatably mounted therein. Extending through a hole in this pin is a rod 54 pivotally connected to lugs 56 on the slide 28. Mounted on the rod 54 between a shoulder on the rod and a washer 58 engaging the pin 52 is a compression spring 60. It will thus be seen that upon movement of the handle 46 toward the handle 12 by one of the operator's hands in engagement with both handles the slide 28 is operated as described through the spring 60 and acts through the spring 40 to move the slide 32 into clamping relation to the fingers 42. At the same time the pinion 20 acts on the bar 14 to press the projections 16 on the bar yielding against the inner face of the lip *a* on the insole. The arm 50 also serves, by the same movement, to operate a needle 62 which engages the portion of the binder material bridging the space between the fingers 42 and forces the material in the form of a loop through the upstanding margin of the upper and the lip of the insole. The needle is secured at its outer end to a block 64 provided with a pin 66 which extends into slots 68 in the forks of the arm 50, and it extends through openings in the slides 28 and 32 with some clearance between it and the slide 28. The needle has a beveled end positioned initially as shown in Figs. 1 and 2 to support the binder material placed upon it between the slide 32 and the fingers 42, and after the material has been clamped by the slide against the fingers further movement of the needle causes its beveled end to deflect upwardly the portion of the material engaged thereby, which is prevented at that time by the fingers from moving with the needle. This portion of the elastic material, upon further movement of the needle, snaps downwardly into a recess 70 extending transversely of the needle, as illustrated diagrammatically in Fig. 5. The needle thereafter carries the material along with it in the form of a loop through the margin of the upper and the lip of the insole, at the same time stretching it by reason of the fact that portions thereof at the sides of the needle are clamped between the slide 32 and the fingers 42. In this operation the material may slip to some extent between the slide and the fingers in response to the pull of the needle thereon. The needle thus passes inwardly between the two projections 16 of the bar 14 which support the lip at its inner side against the thrusts of the needle and are pressed yielding outward against the lip through the action 70 of the spring 60 on the pinion 20. To facilitate

the forcing of the binder material through the upper and the lip, the needle has along its opposite sides grooves 72 (Fig. 5) in which portions of the material are received.

Near the end of the operative movement of the needle 62 the fingers 42 are moved downwardly to release the portions of the binder material clamped between them and the slide 32. For this purpose there is mounted in the rod 44 a pin 74 extending through slots 76 in the casing 10 and also through a short slot 78 formed in one arm of a bell-crank lever 80 pivotally mounted on a pin 82 in the casing. The other arm of this bell-crank lever is pivotally connected to a link 84 provided with a slot 86 through which extends a pin 88 carried by the arm 50. This pin moves idly along the slot until the needle has nearly completed its operative movement and then acts through the link and the bell-crank lever to impart the downward movement to the rod 44. It will be understood that when the fingers 42 are thus moved downwardly the stretched portions of the binder material extending from the fingers inwardly as far as the upstanding margin of the upper contract to their normal condition.

After the operation of the needle the operator releases the handle 46 and permits the handle to be returned by a spring 90 positioned between it and the other handle 12. By the action of this spring, therefore, the needle is withdrawn from the shoe to its initial position, and the slide 28 also is returned by engagement of the pin 52 with a collar 92 fast on the rod 54, the limit of return movement of the handle 46 being determined by engagement of the pin 88 with the link 84 at one end of the slot 86 and by engagement of the pin 74 with the casing 10 at the upper ends of the slots 76. A spring-pressed plunger 94 movable in the casing and engaging the bell-crank lever 80 assists in the return of the rod 44. To prevent the loop *c* of the binder material at the inner side of the lip of the insole from being withdrawn by the return movement of the needle, there is provided a retaining member 96 slidably mounted in the bar 14 and having a hook-shaped lower end 98. A pin 100 extending from the bar into a slot 102 in the member 96 prevents the member from turning and determines the limit of its movement in one direction under the influence of a spring 104. When the needle 62 is moved inwardly its beveled end engages the hook-shaped end 98 of the member 96 and lifts the member against the resistance of the spring 104, after which the hook-shaped end of the member enters a slot 106 (Fig. 5) between two short flanges 108 on the needle and then rides over the binder material and enters another slot 110 in the needle with in the loop of the binder material. As the needle is withdrawn, curved edges of the flanges 108 first lift the portion of the loop engaged thereby, after which the hook-shaped end of the member 96 is engaged and lifted by a curved cam face 112 (Fig. 7) formed on the needle between the flanges, carrying the loop with it as shown in Fig. 8. The loop is thus retained by the hook-shaped end of the member 96 as the needle is further withdrawn, after which it is disengaged from the loop as the operator withdraws the tool from the shoe. The loop thus released is permitted to contract at the inner side of the lip, the increased thickness of the looped material due to such contraction preventing withdrawal of the loop thereafter from the lip and the margin of the upper.

The manner of practicing the method with the assistance of the above-described tool in the last-
ing of the toe end of a welt shoe with a machine such as shown in the previously mentioned Letters Patent will now be briefly summarized. After the machine has come to a stop the first time with the wipers holding the upper in the angle between the feather and the lip of the insole in the manner illustrated in Fig. 6, the operator withdraws a sufficient length of elastic binder material from a suitably supported reel and may pull the material into the recess around the toe between the upper and the wipers 2 at the extreme edge of the shoe bottom with enough force to cause it to remain temporarily in that position. The operator then places the binder-fasterning tool substantially in the position illustrated in Fig. 1 with the projections 16 of the bar 14 resting on the bottom face of the insole at the left-hand side of the shoe bottom, and positions the free end portion of the binder material on the beveled end of the needle 62 between the fingers 42 and the slide 32, as also illustrated in Fig. 1. When the tool is thus initially presented the projections 16 may or may not actually engage the lip of the insole. Thereafter the operator swings the handle 46 to operate the tool in the manner already described in detail, the projections 16 being pressed outwardly against the lip of the insole and portions of the binder material being clamped yielding by the slide 32 against the fingers 42. Continued movement of the handle causes the needle to connect with the portion of the binder material bridging the space between the fingers 42 and to carry the material with it in the form of a loop through the margin of the upper and the lip of the insole while at the same time stretching it, as illustrated in Fig. 6. In this operation the retaining member 96 rides over the binder material to a position where its hooked end 98 is within the loop, as illustrated in Fig. 7 and as already fully described. Near the end of the movement of the needle the fingers 42 are moved downwardly to release the clamped portions of the material. Thereafter the operator releases the handle 46 to permit it to be returned by the spring 90 and thereby to return the operating parts of the tool to their initial positions. In the return of the needle the retaining member 96 is forced upwardly, as shown in Fig. 8, carrying the loop with it, this member preventing the loop from being withdrawn from the lip of the insole and the margin of the upper as the needle is withdrawn.

After having thus fastened the binder material at one side of the shoe bottom, the operator preferably detaches the material extending around the toe from the recess between the wipers 20 and the upper and then applies a pull to the material at the right-hand side of the shoe to stretch it and to draw it more tightly into the recess adjacent to the wipers. While holding the material under tension the operator thereafter starts the machine to cause the wipers partially to retract and to relax their downward pressure on the upper and thereby to permit the binder material to be drawn inwardly under the wipers against the upstanding margin of the upper. As hereinbefore explained, the wipers are then again fully advanced and closed and are forced downwardly against the upper to hold it in fastened position and also to hold the binder material in its stretched condition against the upper. After the machine has again come to a

stop with the wipers in these positions, the operator proceeds to fasten the binder material at the right-hand side of the shoe bottom in the same manner as previously at the left-hand side, as illustrated in Fig. 9. In thus operating at the right-hand side the operator, in positioning the material on the beveled end of the needle between the fingers 42 and the slide 32, applies a pull thereto to stretch to some extent the portion of the material extending from the adjacent wiper 2 to the fingers 42. Accordingly, when the fingers are moved downwardly to release the clamped material near the end of the operative movement of the needle, the contraction of the portion of the material extending beyond the wiper 2 will cause it to snap in against the upper, so that no objectionable loosening of the binder will take place when the wipers are withdrawn from the shoe. After thus fastening the binder material at the right-hand side of the shoe the operator severs the portion applied to the shoe from the rest of the material, cutting the material at such a point as to leave only a very short end thereof projecting from the margin of the upper. Preferably also he similarly trims the projecting end portion of the material at the left-hand side of the shoe.

It will be understood that the elastic binder applied and fastened to the shoe in the manner described serves effectively in its stretched condition to hold the upstanding margin of the upper with a constant force against the lip of the insole, any loosening of the binder being prevented by reason of the increase in thickness of the material forming the loops at the inner side of the lip after the loops have been forced inwardly in a stretched condition and released. It will further be evident that the elastic binder will not be in the way of the welt when the latter is applied to the shoe and will not interfere with the needle of the welt-sewing machine. The nature of the binder applied and fastened as described is, moreover, such that it need not be removed from the shoe, although obviously it may be removed if desired.

Novel features of the binder-fastening tool herein shown and described are claimed in a divisional application Serial No. 21,368, filed on April 16, 1948.

Having described the invention, what I claim as new and desire to secure by Letters Patent of the United States is:

1. That improvement in methods of lasting shoes which consists in working an end portion of an upper on a last into lasted position, applying about the end of the upper an upper-holding binder of elastic material in a stretched condition, and fastening the binder to the shoe to hold it in its stretched condition by forcing it through portions of the shoe materials at the opposite sides of the shoe bottom.

2. That improvement in methods of lasting shoes which consists in working an end portion of an upper on a last into lasted position with its margin in upstanding position over the shoe bottom, applying to the upstanding margin of the upper around the end of the shoe bottom an upper-holding binder of elastic material in a stretched condition, and fastening the binder to the shoe to hold it in its stretched condition.

3. That improvement in methods of lasting shoes which consists in working an end portion of an upper into lasted relation to a last and an insole on the last with its margin in upstanding position against a lip on the insole, applying to the upstanding margin of the upper around the end

5 of the shoe bottom an upper-holding binder of elastic material in a stretched condition, and fastening the binder to the lip at the opposite sides of the shoe bottom to hold it in its stretched condition.

4. That improvement in methods of lasting shoes which consists in working an end portion of an upper into lasted relation to a last and an insole on the last with its margin in upstanding position against a lip on the insole, applying to the upstanding margin of the upper around the end of the shoe bottom an upper-holding binder of elastic material in a stretched condition, and fastening the binder to the shoe at the opposite sides of the shoe bottom to hold it in its stretched condition by forcing portions of it inwardly through the margin of the upper and the lip of the insole.

20 5. That improvement in methods of lasting shoes which consists in working an end portion of an upper into lasted relation to a last and an insole on the last with its margin in upstanding position against a lip on the insole, applying to the upstanding margin of the upper around the end of the shoe bottom an upper-holding binder of elastic material in a stretched condition, and fastening the binder to the shoe at the opposite sides of the shoe bottom by forcing portions of it in a stretched condition inwardly through the margin of the upper and the lip of the insole and releasing them to permit them to resume their 25 normal condition at the inner side of the lip.

30 6. That improvement in methods of lasting shoes which consists in working an end portion of an upper into lasted relation to a last and an insole on the last with its margin in upstanding position against a lip on the insole, applying to the upstanding margin of the upper around the end of the shoe bottom an upper-holding binder of elastic material in a stretched condition, and fastening the binder to the shoe at the opposite sides of the shoe bottom by forcing portions of it in a stretched condition inwardly through the margin of the upper and the lip of the insole 35 and releasing them to permit them to contract at the inner side of the lip.

40 7. That improvement in methods of lasting shoes which consists in working an end portion of an upper into lasted relation to a last and an insole on the last with its margin in upstanding position against a lip on the insole, fastening a strand of elastic binder material to the shoe at one side of the shoe bottom by forcing a portion 45 thereof in a stretched condition inwardly through the margin of the upper and the lip of the insole and then releasing it to permit it to contract at the inner side of the lip, and thereafter stretching the binder material lengthwise of the edge of the 50 shoe bottom in engagement with the upstanding margin of the upper around the end of the shoe bottom and similarly fastening it to the shoe at the other side of the shoe bottom.

55 8. That improvement in methods of lasting shoes which consists in working an end portion of an upper into lasted relation to a last and an insole on the last with its margin in upstanding position against a lip on the insole, fastening a strand of elastic binder material to the shoe at one side of the shoe bottom by forcing a portion thereof in the form of a loop inwardly through the margin of the upper and the lip of the insole 60 in a stretched condition and then releasing the loop to permit it to contract at the inner side of the lip, and thereafter stretching the binder ma- 65

terial lengthwise of the edge of the shoe bottom in engagement with the upstanding margin of the upper around the end of the shoe bottom and similarly fastening it to the shoe at the other side of the shoe bottom.
